UNITED STATES PATENT OFFICE.

JOHN J. MULLANEY, OF NEW YORK, N. Y.

POCKET-LAMP.

1,026,995.

Specification of Letters Patent.

Patented May 21, 1912.

Application filed February 9, 1911. Serial No. 607,718.

To all whom it may concern:

Be it known that I, JOHN J. MULLANEY, a citizen of the United States, residing at New York, in the county of New York and State of New York, have invented certain new and useful Improvements in Pocket-Lamps, of which the following is a full, clear, and exact specification.

This invention relates to pocket lamps, 10 and has special reference to devices adapted for lighting cigars, etc., comprising a fuel reservoir and a wheel which is mechanically actuated to produce the igniting sparks.

The object of the invention is to simplify 15 and improve the mechanism of such devices, whereby they will be rendered more reliable in action and cheaper to produce.

My improvements are principally confined to the mechanism for actuating the 20 wheel, whereby I have dispensed with rack and pinion mechanism and have devised a pawl and ratchet mechanism whereby the wheel is positively stopped after a predetermined throw and also the same mechanism 25 positively stops the lid.

Further improvement consists in the mechanism for holding a pyrophorous alloy in contact with the wheel, said alloy also acting to hold the wheel against rearward 30 movement by the pawl when the lid is shut.

A further feature of improvement consists in mounting various parts on a single support, which can be assembled and then placed in the box.

35 Further features of improvement consist in the construction, arrangement and details of the various parts, as will more fully appear in connection with a description of the accompanying drawing, wherein—

40 Figure 1 is a side view on an enlarged scale of a lamp embodying the invention, and Fig. 2 is an end view.

1 represents a box or casing having a liquid reservoir 2 adapted to contain a wick

45 3 which extends upward through a wick tube 4 secured to the top of the reservoir, and within the top of the box.

50 5 represents a lid pivoted at 6, and 7 represents an operating button controlling the catch 8, these parts being constructed in a well known manner. 9 represents a filling aperture which is to be closed by a pivoted cap 10, which has a stop projection 11 or other suitable closure.

55 12 represents a coiled spring carried on a

post 13 and bearing on a pin 14 carried by the lid 5. Spring 12 also has a hooked end portion 16 which acts to stop the lid at the dotted position shown in Fig. 1.

17 represents a bridge piece having vertical inturned flanges 18 and a cross member 19 connecting the sides 17.

20 represents a wheel carried on shaft 21 journaled in opposite sides of the bridge piece, the edge of the wheel being corrugated or knurled in the usual manner. On one side, the flint wheel 20 bears against the flanges 18 and on the other is provided with four laterally projecting pins 22, which are of such length as to almost touch the bridge 65 piece 17, thereby holding the wheel 20 in position. In order to actuate the wheel 20, a pawl 24 is mounted on the pin 14. This pawl is held in engagement with the pins 22 by a spring 25. The pawl 24 comprises 70 a hooked portion 26 which directly engages with the lower pin 22 as the lid opens, and a straight edge 27 of such length that when the pawl is in the dotted position shown in Fig. 1 and having the hooked portion engaged with one of the pins 22 the elongated edge 27 is engaged with the following pin 22. By reason of the engagement of the pawl after a predetermined definite movement with two pins on opposite sides of the 75 edge 27, further movement of the wheel is positively stopped, and also further movement of the lid. When the lid is shut, it will be seen that the straight face 27 of the pawl rides down on the lower pin 22 until 80 the spring snaps the pawl upward to the position shown in Fig. 1. Thus it will be seen that when the catch 8 is released the spring 12 bearing on the pin 14 throws the lid upward, which carries the pawl with it 85 and thereby pulls the friction wheel with a very quick and sharp motion, until the lid stops by the locking of the pawl with two of the pins.

88 represents a pyrophorous alloy, of suitable composition, which bears on the surface of the wheel 20, the alloy being held in a small three sided box formed on the bridge piece 19. The alloy is pressed downwardly by one end of a spring 29, the other end of 100 which is carried in an upturned extension 30 of the bridge piece 19, which extension has a projecting notch as at 31 with which the other end 32 of the spring 29 is engaged. By disengaging the end 32 of the spring 110

29 from the notch 31 the spring is released and allows the alloy 28 to be removed or inserted.

From the foregoing description it will be seen that the wheel and pyrophorous alloy are all mounted on a single member, and can be assembled and then readily secured in the top of the box.

33 represents the usual closure tube for 10 covering the end of the wick when the lid is shut, to prevent formation of gases and flashing when the lid is opened. It will be seen that I have provided a pulling pawl mechanism for actuating the flint wheel, and 15 which is operated by the momentum of the lid and the spring 20.

By the within described construction the cost of production is very materially cheapened, and also a device is provided which 20 is simple and reliable in in operation.

Various modifications and changes within the scope of the appended claims may be made without departing from the invention.

25 Having thus described my invention, what I claim as new and desire to secure by Letters Patent is:

1. In a spark producing device, the combination with supporting means, of a wheel 30 carried thereby having actuating projections, a movable pawl for engaging said projections when moved in one direction to rotate the wheel, a pyrophorous alloy bearing on said wheel, and means for moving 35 said pawl to operate said wheel a predetermined distance, said pawl after a predetermined movement positively interlocking with said projections to stop the wheel.

2. In a spark producing device, the combination with spark producing means comprising a rotatable wheel and a pyrophorous alloy, of actuating means comprising a movable pawl engaging projections of said wheel when moved in one direction, means 45 for moving said pawl, and means carried by said pawl for positively stopping the movement of said wheel at a predetermined point.

3. In a spark producing device, the combination with spark producing means comprising a rotatable wheel and a pyrophorous alloy, of lateral projections carried by said wheel, a pawl adapted to engage said projections to operate said wheel when moved in one direction, said pawl and projections 55 cooperating after a predetermined throw of the wheel to positively stop further movement.

4. The combination with a box having a reservoir and a hinged lid, of a spring tending to open the lid, a latch holding the lid

closed, a pawl carried by the lid, a bridge piece secured to the box above the reservoir and carrying a friction wheel, a pyrophorous alloy and means for resiliently pressing the alloy against the wheel, the pawl engaging and rotating said wheel only in one direction when the lid opens, and moving back to reengage the wheel when the lid closes.

5. In a sparking device, the combination with a rotatable friction wheel and a pyrophorous alloy bearing thereon, of a pawl 70 for intermittently engaging and rotating the wheel in one direction by a pulling stroke, said pawl positively interlocking with and stopping the wheel after a predetermined 75 stroke, and moving backward without rotating the wheel.

6. The combination in a spark producing device, with a wheel having separated lateral projections, of a movable pawl having 80 a hook to engage one of said projections at a time to rotate the wheel and a point to be engaged by the succeeding projection to positively stop the wheel after a predetermined movement.

7. The combination in a spark producing device, with a wheel having separated lateral projections, of a pawl mounted to be bodily movable longitudinally of its length, said pawl having a hook adjacent its rear 90 end to engage one of said projections at a time to rotate the wheel, and rearwardly of said hook having a point to be engaged by the succeeding projection to positively stop the wheel after a pre-determined pulling 95 movement, said pawl also having an inclined face between said hook and point to cause the pawl to ride over said succeeding wheel projection when moved back to its original position.

100 8. The combination in a spark producing device, with a reservoir having a spring actuated hinged lid, and latching means for holding the lid closed, of a bridge piece mounted to be detachably secured within 105 said reservoir casing to be covered by the closed top, said bridge piece carrying a rotatable wheel, and a pyrophorous spring pressed alloy bearing on the periphery of the wheel, and a spring pressed pawl pivoted on the lid and engaging said wheel to rotate it a pre-determined distance when the lid is opened.

110 In testimony whereof I affix my signature, in presence of two witnesses.

JOHN J. MULLANEY.
